[57] CLAIM

The ornamental design for a cordless vacuum cleaner, as shown and described.

DESCRIPTION

FIG. 1 is a perspective view of a cordless vacuum cleaner showing our new design;

FIG. 2 is a perspective view thereof with the handle removed;

FIG. 3 is a side elevational view thereof;

FIG. 4 is a side elevational view thereof, of the opposite side of FIG. 3;

FIG. 5 is a top plan view thereof;

FIG. 6 is a bottom plan view thereof;

FIG. 7 is a front elevational view thereof;

FIG. 8 is a rear elevational view thereof;

FIG. 9 is a front perspective view thereof;

FIG. 10 is a rear perspective view thereof;

FIG. 11 is a front perspective view of the vacuum cleaner dismounted;

FIG. 12 is a rear perspective view thereof;

FIG. 13 is a side elevational view thereof;

FIG. 14 is a side elevational view thereof of the opposite side of FIG. 13;

FIG. 15 is a top plan view thereof;

FIG. 16 is a bottom plan view thereof;

FIG. 17 is a front elevational view thereof; and,

FIG. 18 is a rear elevational view thereof.

The handle is shown broken away in FIGS. 3-6 and 9-10, for ease of illustration. The vacuum cleaner shown in FIGS. 11-18 is shown separately for clarity of illustration.
